US00D799967S

(12) **United States Design Patent** (10) **Patent No.:** **US D799,967 S**
Wade (45) **Date of Patent:** **** Oct. 17, 2017**

(54) **PLASTIC BOTTLE**

(71) Applicant: **Industries Lassonde Inc.**, Rougemont (CA)

(72) Inventor: **Dena Wade**, Cumming, GA (US)

(73) Assignee: **Industries Lassonde Inc.**, Rougemont (CA)

(**) Term: **15 Years**

(21) Appl. No.: **29/551,647**

(22) Filed: **Jan. 15, 2016**

(51) LOC (10) Cl. **09-01**

(52) U.S. Cl.

USPC **D9/500**; D9/549

(58) **Field of Classification Search**

(57) **CLAIM**

I claim the ornamental design for a plastic bottle, as shown and described.

DESCRIPTION

FIG. 1 is a top perspective view of a plastic bottle showing my new design;

FIG. 2 is a bottom perspective view of the plastic bottle of FIG. 1;

FIG. 3 is a right side elevation view of the plastic bottle of FIG. 1;

FIG. 4 is a left side elevation view of the plastic bottle of FIG. 1;

FIG. 5 is a top plan view of the plastic bottle of FIG. 1; and,

FIG. 6 is a bottom plan view of the plastic bottle of FIG. 1.

1 Claim, 3 Drawing Sheets
